(57) **CLAIM**

The ornamental design for a vehicle air vent, as shown and described.

DESCRIPTION

FIG. 1 is a perspective view of a vehicle air vent, according to a first embodiment of the invention.

FIG. 2 is a perspective view of a vehicle air vent, according to a second embodiment of the invention.

FIG. 3 is a perspective view of a vehicle air vent, according to a third embodiment of the invention.

FIG. 4 is a perspective view of a vehicle air vent, according to a fourth embodiment of the invention.

FIG. 5 is a perspective view of a vehicle air vent, according to a fifth embodiment of the invention.

FIG. 6 is a perspective view of a vehicle air vent, according to a sixth embodiment of the invention; and,

FIG. 7 is a perspective view of a vehicle air vent, according to a seventh embodiment of the invention.

The broken line showing of a vehicle air vent is included for the purpose of illustrating portions of the article and forms no part of the claimed design. The broken line showing of any remaining structure is included for the purpose of illustrating environmental structure and forms no part of the claimed design.

1 Claim, 7 Drawing Sheets
